SLEEVE CONSTRUCTION

Israel L. Freedman, Washington, D. C.

Application April 17, 1944, Serial No. 531,442

1 Claim. (Cl. 2—125)

(Granted under the act of March 3, 1883, as
amended April 30, 1928; 370 O. G. 757)

1

The invention described herein, if patented, may be manufactured and used by or for the Government for governmental purposes, without payment to me of any royalty thereon.

This invention contemplates the provision of a sleeve which fits closely under the arm of the wearer but which does not bind and will not rip or tear easily.

It has been a fault in clothing designed for persons leading active lives, as members of the armed forces, laborers and athletes, that the sleeves of upper body garments of various types were either too tight, resulting in binding, chafing, wearing and ripping of the seams, or too loose, resulting in a poor fit, untidy appearance, too great bulk under the outer garments, lack of warmth in cold climates or in cold weather and even in so much fullness as to interfere with the movements of the wearer.

It is the object of the present invention to provide a sleeve which avoids the difficulties due both to tightness and to looseness, and which fits closely and permits free stretching at the same time.

It is a further object of the invention to provide a sleeve having an underarm extension projecting above the normal underarm line and folded downwardly to approximately that line, the free edge of said downwardly turned portion being seamed flatwise to the armhole of the garment body, the fold of material providing an effective elongation of the underarm length of the garment when the wearer's arm is raised.

Further objects of the invention will be apparent from a consideration of the following description taken in connection with the accompanying drawing, in which,

Fig. 1 is a perspective view of a soldier wearing a garment having the improved sleeve construction.

Fig. 2 is a perspective view of a part of the right sleeve raised above and separated from the adjacent body portion.

Fig. 3 is a plan view of the upper portions of the patterns of the two sleeves sections and

Fig. 4 is a fragmentary perspective view on a larger scale of the underarm portion of the left sleeve and adjacent body portion.

As shown in the drawing the invention comprises a garment having a body A and a sleeve B secured together by the seam 10. The sleeve B is formed of two sections as indicated particularly in Fig. 3, an underarm section 11 and a top

2

section 12. The two sections are joined by seams 13 and 14 as indicated in Fig. 2. The tops of the two sections are cut in a peculiar configuration to furnish semi-circular extension 15 integral with the sections at the under arm portions. The extension 15 is bisected by a dart 16 in the part formed on the sleeve section 11, which when the sleeve is sewed into the body of the garment forms an extension of the underarm body seam 17. The semi-circular extension 15 is formed of separate flaps or extensions 18 and 19 on the section 11, these extensions being separated by the dart 16, and a flap or extension 20 on the sleeve section 12. The dart 16 is formed by removing a portion 15 of the material to form a notch 21 having a straight side 22 and a side 23 having an outwardly extending angle 24, and seaming the sides 22 and 23 together.

When the sides of the notch 21 are seamed together to form the dart 16 the angle 24 causes a slight drawing in of the extension at its base which causes the finished sleeve to tend to fold at the line O—X as indicated in Figure 4. This fold, which fits closely under the armpit, stretches 25 freely lengthwise when the wearer's arm is raised.

As shown in Fig. 1, the jacket having the improved sleeve construction permits the wearer to raise his arm without having the bottom of the jacket pull up at the waist. This construction 30 gives a maximum of freedom of motion without the provision of extra material or folds or fullness of any sort, thus producing a very well fitting garment. It also reduces the tension on the seam which secures the sleeve on the armhole, which otherwise might be subjected to strains sufficient to tear the fabric or rip the stitches. The garment is exceedingly neat in appearance and gives the greatest possible comfort, particularly when worn under over-garments having moderately close fitting sleeves.

Having thus described my invention what I claim is:

A garment sleeve comprising separate top and undersleeve parts seamed together, a foldable extension on the upper end of the undersleeve part, said extension having a cut-out extending lengthwise of the sleeve between the seams, said cutout being wider at the fold line of the extension and tapering toward the ends, whereby a constriction 45 is produced which tends to maintain the fold upright in a completed garment.

ISRAEL L. FREEDMAN,
